ATTORNEY

UNITED STATES PATENT OFFICE.

CHARLES W. PIERCE, OF OAK HILL, NEW YORK.

WARDROBE-HOOK.

SPECIFICATION forming part of Letters Patent No. 402,966, dated May 7, 1889.

Application filed April 16, 1888. Serial No. 270,753. (No model.)

To all whom it may concern:

Be it known that I, CHARLES W. PIERCE, of Oak Hill, Greene county, New York, have invented a new and useful Improvement in Wardrobe-Hooks, of which the following is a specification.

My invention consists of a one-hole wardrobe-hook with a brace, constructed as hereinafter described, reference being made to the accompanying drawings, in which—

Figure 1 is a side elevation of my invention, and Fig. 2 is a front view.

Wardrobe-hooks *a b* have been made with a brace, *c*, heretofore, but always with a lateral extension of the base-plate *d* each side of the arm *a* and brace *c*, and with a hole in each extension, making two holes for attaching screws, one of which may be dispensed with, for economy of material and labor, by the contrivance which I have adopted, viz: widening and thickening the base-plate *d* between the brace *c* and hook-prong *b*, and elongating it a little thereat and making the single screw-hole *e* through it, together with the spur *f* at

the back and lower end of the base-plate, to 25 be pressed into the wood for a stay to prevent the turning of the hook on the screw. I make the hole *e* as much higher than the projecting end of prong *b* as will allow the screw-driver to work freely over said prong to insert the 30 screw.

I cast the hook on a chill core to make the screw-hole, and thus save the cost of drilling and countersinking the hole; but may drill the hole, if preferred.

What I claim, and desire to secure by Letters Patent, is—

The improved wardrobe-hook, comprising the upper arm or hook, *a*, brace *c*, lower hook, *b*, and base-plate *d*, and having the attaching 40 screw-hole *e* of the base-plate between the brace and the lower hook, but above or out of interfering range of the point of said hook with the driving of the screw.

CHARLES W. PIERCE.
